REGENERATIVE AIR PREHEATING

George H. Isley, Worcester, Mass., assignor to
 Morgan Construction Company, Worcester,
 Mass., a corporation of Massachusetts

Application November 19, 1931
 Serial No. 576,194

15 Claims. (Cl. 263—19)

The present invention relates to the preheating of the air that is used to support combustion of fuel,—particularly fuel of relatively low heat value, in order to obtain, by the combustion of said fuel, a high flame temperature.

Ordinary recuperative preheating of air and also ordinary regenerative preheating of air make use, as heating agents, of waste furnace gases that have already been reduced in temperature to such a degree that they cannot be used to provide the continuous supply of highly preheated air that is required, for example, when blast furnace gas, or other fuel having a relatively low heat value, is used as the fuel for steam boilers, continuous heating furnaces and the like. Under such conditions, the preheating to a high temperature of the air for combustion must be obtained by the burning of fresh fuel, and the present invention contemplates a new and improved regenerative preheating system for this purpose, so arranged as to supply highly preheated air at any desired positive pressure and temperature in a continuous flow to the station or stations where such fuel is to be burned, and where a high flame temperature is required.

The attainment of the above and other objects and advantages of my invention will be set forth in detail hereinafter, reference being had in this connection to the accompanying illustrative drawings, in which—

Fig. 1 is a view in side elevation, partly in section, of one form of apparatus by which my improved regenerative preheating system may be put into effect.

Fig. 2 is a transverse sectional view of the apparatus shown in Fig. 1.

Fig. 3 is a diagrammatic plan view of another arrangement of apparatus for carrying out the invention.

Fig. 4 is a sectional view on the line 4—4 of Fig. 3.

Like reference characters refer to like parts in the different figures.

In the specific embodiment of my invention shown in Figs. 1 and 2, the numeral 1 indicates a delivery pipe or conduit for the highly preheated air produced continuously, as hereinafter described, by my improved system,—this pipe leading to the station or stations, not shown, where such air is to be used for supporting combustion of low grade fuel, in order to secure, by such combustion, a high flame temperature. Adjacent the pipe 1, and suitably connected thereto, as hereinafter described, are a pair of regenerators 2 and 2'. These regenerators are alike

in construction, each providing two chambers 3 and 3a of the usual checkerwork construction, or its equivalent, the chambers being separated from each other by a partition or wall 4 which, as shown in Fig. 1, has its lower edge spaced from the bottom of the regenerator, thereby to afford communication between the chambers 3 and 3a at this point.

The pipe or conduit 1 has suitable branches 5, 5' that communicate, respectively, as shown at 6, 6', with the two regenerator chambers 3, 3, near the upper ends of the latter, and in these connections 6 and 6' are disposed suitable fuel burners 7 and 7', respectively, each adapted, at the proper times, to be supplied with fuel, such as blast furnace gas or the like, for burning in the regenerator chambers 3, 3,—the burners 7 and 7' for this purpose being connected to branches 8 and 8', respectively, of a fuel pipe 9, the latter being connected to a supply pipe 10.

All the air supplied to my improved system, including that which supports the combustion of fresh fuel at the burners 7 and 7', as well as that which forms the continuous supply of preheated air taken off by the pipe or conduit 1, is handled by a blower 11 which is continuously driven, as by a motor 12, and which delivers said air under pressure, in the arrangement of apparatus here shown, to a duct 13 having an outlet 14 to the atmosphere, and also having branches 15 and 15', respectively, connected to the upper ends of the two regenerator chambers 3a, 3a. At the juncture of said branches 15 and 15' with said duct 13, is disposed a reversing valve 16 which, in the position illustrated in Fig. 1, directs all the air from duct 13 through branch 15' into the chamber 3a of regenerator 2', said air passing downwardly through said chamber and then upwardly through the chamber 3 of regenerator 2'; from which it is delivered by branch 5' to the air conduit 1,—it being understood that, under these conditions, the operation of the fuel burner 7' has, for the time being, been discontinued, as by the shunting off of the fuel supply to the other burner 7, through the agency of a reversing valve 17 at the juncture of the branch fuel pipes 8, 8' with the pipe 9.

Prior to this movement of valve 17 into a position which directs the gaseous fuel to the burner 7, the burner 7' has for a period been operative, thus to store up heat in the checkerwork or the like of the chambers 3 and 3a of regenerator 2'; therefore, under the conditions above set forth, the air handled by blower 11, all of which, as above stated, reaches the conduit 1 by way of

regenerator 2', acquires, by passage through said regenerator, a very high temperature. A relatively small portion of this highly heated air, as shown by the broken line arrows in Fig. 1, flows 5 through the conduit 1 and branch 5 to the burner 7, to support combustion of the fresh fuel supplied to said burner by the branch fuel pipe 3, thus to give a high flame temperature by the burning of said fuel; the balance of this highly 10 heated air is conveyed through the pipe 1 to the station or stations, not shown, where low grade fuel is being burned and where a high flame temperature is desired. The combustion products from the operative burner 7 pass downwardly in 15 the chamber 3 of regenerator 2 and then upwardly in the chamber 3a of said regenerator, to which chambers they give up their heat before making exit, by way of branch connection 15 to the outlet opening 14 at the upper end of duct 13,—being directed into said outlet 14 by the valve 16 in the position of the latter shown by Fig. 1.

When the valves 16 and 17 are simultaneously reversed, in the manner hereinafter described, all the air forced into the system by blower 11 is 20 directed through branch 15 into the regenerator 2, and the combustion of fresh fuel for the regenerative preheating of the air supply is transferred from the burner 7 to the burner 7'. Under these 25 conditions, it will be understood that the air in its passage through the previously-heated chambers 3 and 3a of regenerator 2 will acquire the desired high temperature before making its exit, at the top of chamber 3, into the branch 5 of hot air conduit 1. The continuous supply of highly 30 heated air to the latter is thus maintained when the apparatus is reversed, a relatively small portion of said air being, under these conditions, drawn off through branch 5' to support the combustion of the fuel delivered by burner 7', which 35 is now operating to heat up the checkerwork of the regenerator 2'. These combustion products from regenerator 2' leave the chamber 3a of said regenerator by the branch pipe 15', and are directed by the valve 16 to the outlet 14.

40 The volume of air which is forced into the system, under pressure, by the blower 11 is maintained at all times in substantially constant proportion to the total amount of low grade fuel, supplied by pipe 10, which is being burned at 45 the several stations not shown, with the aid of the air, supplied by pipe 1, that is preheated by said system. That is to say, the air supply duct 13 is provided with a damper 18 which is operated automatically to increase or decrease the air supply in proportion to increases or decreases 50 in the amount of fuel flowing to the fuel-burning stations through the main fuel supply pipe 10. To this end, the damper 18 is suitably connected to a pressure regulator 19 of any well known type, 55 the latter, as shown, having connections 20 and 21, respectively, to the fuel pipe 10 and air duct 13, whereby, in response to variations of demand on the fuel supply, the regulator 19 produces such movement of damper 18 as to produce corresponding variations in the flow of air to the 60 system, thus maintaining, in the operation of the system, the desired quantitative ratio of air supply to fuel supply most favorable to proper combustion of said fuel. A similar automatic pressure regulator 22, having connections 23 and 24, respectively, to the fuel branch pipe 9 for burners 7 and 7' and to the outlet portion 14 of air duct 13, is provided for the actuation of a damper 25 in said outlet portion 14. A valve 26 is provided 65 in the fuel branch pipe 9 to regulate the

amount of fuel passing to burner 7 or to burner 7', whichever is operative. The joint regulation of the fuel and heated air admitted to the fuel-burning regenerator is obtained by holding substantially constant the pressure prevailing in said 80 regenerator and by keeping such pressure below that prevailing in the other regenerator. Manifestly, the exit temperature of the combustion products from the fuel-burning regenerator tends to rise gradually all during each period of use of 85 said regenerator as a fuel-burning instrumentality, and this rise of temperature, being accompanied, of course, by an increase in the volume of the combustion products, would produce a rise 90 of pressure in said fuel-burning regenerator, but for the fact that the regulator 22, acting on damper 25, exerts a corrective influence by balancing the pressure in outlet 14 against the fuel flow pressure in the connection 8. By thus maintaining substantially constant the pressure in 95 the fuel-burning regenerator, the amount of heated air entering said regenerator is kept substantially constant and therefore in the proper proportion to the amount of fuel admitted by valve 26. In this way the heated air from supply 100 pipe 1 flows through branch 5 or 5', as the case may be, in the proper proportion to give the desired quantitative ratio of air supply to fuel supply most favorable to proper combustion at the 105 burner 7 or 7', as the case may be.

In the operation of my improved system, the pipe 1 will be continuously supplied with highly preheated air, this result being obtained by periodic reversals of damper 16 and valve 17, so that first one and then the other of the two 110 regenerators 2 and 2' is used to impart its heat to the entire supply of air blown in under pressure by blower 11,—meanwhile the other regenerator not so used being heated up to a high temperature by the burning therein of fresh fuel, 115 as above described. Such periodic reversal of damper 16 and valve 17, to substitute one regenerator for the other as the heating agent for the air supply may, according to my invention, be effected manually; however it is preferable to 120 make the reversals occur automatically, in response to temperature conditions in the system, and to this end the invention contemplates, in one of its aspects, the provision of a thermostat or thermocouple 27 located in the outlet 14 for 125 the combustion products, to secure, periodically, the actuation of a control switch 28, operatively connected, as shown in Fig. 1, to both the damper 16 and the valve 17. Assuming the burner 7 to have been made operative for the combustion of 130 fresh fuel in the regenerator 2, while the air supply is being forced through the regenerator 2', it will be evident that at the start of such operation, the products of combustion leaving the cold end of regenerator 2 by way of branch 135 15 and outlet 14 will be relatively cool, having given up most of their heat to the checkerwork chambers 3 and 3a of said regenerator 2. Under these conditions, said products of combustion will have no effect on the thermocouple 27. However, after operation in this manner for some time, the checkerwork chambers 3 and 3a of regenerator 2 will become hotter and hotter until, finally, they can no longer acquire any further 140 rise in temperature from the passage there- through of said combustion products. The latter will then pass to the outlet 14 at a relatively high temperature, sufficient to affect operatively the thermocouple 27, thereby to actuate the switch 28 for the reversal of damper 16 and valve 17. 150

By such reversal, as heretofore described, the burning of fuel is transferred to the regenerator 2', and the highly heated regenerator 2 becomes the heating agent for all the air supplied under pressure by the blower 11. Thereafter, the regenerators 2 and 2' will interchange their functions automatically at each operation of the thermocouple 27, which indicates approximately the absorption of heat by one or the other of said regenerators to its full capacity.

In order to maintain a substantially constant temperature for the preheated air supply in the pipe 1, the latter is preferably equipped with a thermostat or thermocouple 29, suitably connected, as shown in Fig. 1, to an operating switch 30 for a damper or valve 31 located in a by-pass duct 32, directly connecting the duct 13 with the pipe 1. In the event of an overheated air supply in pipe 1, the thermocouple 29 is responsive to temperature procure, through switch 30, the opening of the normally closed valve or damper 31, allowing some cold air to be diverted from the duct 13 to lower the temperature of the preheated air in the pipe 1; when the thermocouple 29 is no longer affected by the temperature, the switch 30 procure the closure of the valve 31.

It will be noted that the system of my invention produces continuously a supply of highly preheated air under positive pressure, and that the temperature and pressure conditions of such preheated air supply can be varied over a considerable range, to adapt them to the demands of the station or stations, not shown, to which the preheated air is conveyed by pipe 1 for supporting combustion of the fuel and for obtaining a high flame temperature. It will be understood that the apparatus herein disclosed for regeneratively preheating this continuous air supply under pressure is merely illustrative, and that the arrangement and construction of said apparatus is susceptible of wide variation from the present disclosure without departing from the principles and spirit of my invention. For example, if desired, the regenerators, instead of being separate, could be combined in a single unitary structure, or, under either of the conditions specified (separate or combined) could provide for gaseous flow in only one direction, instead of the up and down flow required by the partitions 4, 4'.

As illustrative of further variations in the regenerative air preheating system of my invention, reference is directed to Figs. 3 and 4, showing a system that uses three regenerators, in any of which fuel may be burned for the purpose of maintaining a continuous supply of highly preheated air in a delivery pipe or conduit 41, the latter corresponding to the pipe or conduit 1 of Figs. 1 and 2. The three regenerators are designated 42, 42' and 42'' respectively, and each may be of the construction shown in Figs. 1 and 2, with two chambers 3 and 3a separated from each other by a partition or wall 4. Also, the same as in Figs. 1 and 2, the delivery pipe 41 for preheated air has branches 5, 5' and 5'' that communicate respectively, as shown at 6, 6' and 6'', with the several regenerator chambers 3, 3, 3a, near the upper ends of the latter, and these connections 6, 6' and 6'' are disposed the fuel burners 7, 7' and 7'' respectively, each adapted, at the proper time, to be supplied with fuel through suitable branches 8, 8' and 8'', leading from the fuel pipe 9', the latter being connected, the same as in Figs. 1 and 2, to a fuel supply pipe 10'.

All the air that is supplied to the system shown in Figs. 3 and 4 is handled by a blower 11', which

is continuously driven as by a motor 12', and which delivers said air under pressure to a duct 43, corresponding substantially in function to the duct 13 of Figs. 1 and 2. This duct 43 provides three outlets 44, 44' and 44'' to the atmosphere, one for each of the three regenerators, each of the latter having its chamber 3a connected to the appropriate outlet by a branch pipe, the three branch pipes being designated, respectively, 45, 45' and 45''. At the juncture of each said branch pipe with the outlet from its regenerator is disposed a valve or damper 46, adapted in one position (when fuel is being burned in the associated regenerator), to direct the combustion products into the outlet, and adapted in its other position (when the associated regenerator is being employed for the heating of air), to direct air from the duct 43 into the chamber 3a of said regenerator.

As shown in Fig. 4, suitable linkage 46a is provided, to connect each of the three valves or dampers 46 with an associated valve 47 in the fuel supply line of the same regenerator; by this linkage, when a valve 46, for example, is in the position shown in Fig. 4, the corresponding fuel valve 47 is open, to permit the passage of fuel to be burned to the associated regenerator, but when the valve 46 is shifted to its other position, for the admission of air to said regenerator, then the valve 47 will be moved to closed position, shutting off the fuel supply to that particular regenerator.

Substantially the same means as shown in Figs. 1 and 2 for maintaining the correct proportion of the air supply to the total amount of fuel being burned, is provided in the arrangement of Figs. 3 and 4, there being a damper 18' in the air supply duct 43, which is suitably connected to a pressure regulator 19', the latter, as shown, having connections 20' and 21', respectively, to the fuel pipe 10' and to the air duct 43, whereby, in response to variations of demand on the fuel supply, the regulator 19' produces such movement of damper 18' as to produce corresponding variations in the flow of air to the system. Also, associated with each outlet 44, 44' or 44'' from each regenerator, is a similar automatic pressure regulator 22', having connections 23' and 24', respectively, to the fuel inlet branch and to the waste gas outlet of the associated regenerator; this regulator 22', in each instance, actuates a damper 25' in the corresponding outlet 44, 44' or 44'', as the case may be. Inasmuch as the fuel inlet to each regenerator has a fuel regulating valve 26', to adjust the amount of fuel passing to its burner, it will be clear that the position of damper 25', controlling the outflow of the products resulting from the combustion in the associated regenerator, is automatically determined by the associated regulator 22', in such manner that the volume of combustion products passing said damper 25' and exhausting to the atmosphere is directly proportional to the amount of fuel admitted by valve 26' to the associated regenerator; hence the preheated air which provides the greater portion of the volume of said combustion products is drawn from the air supply main 41 in the proper proportion to give the desired quantitative ratio of air supply to fuel supply most favorable to proper combustion of the fuel being burned in the associated regenerator.

In the operation of the system shown in Figs. 3 and 4, one of the regenerators, such as 42, may be employed for the burning of fresh fuel,

while the other two regenerators 42' and 42'', having been previously heated, may be employed for raising the temperature of the air that is being continuously supplied to the system. Or, 5 if desired, fuel may be burned in two regenerators, while air is being heated in only one of them. In any case, the change in the operating function of any regenerator (from fuel burning to air heating, or vice versa) may be effected by 10 periodic shifting of its associated damper 46 and fuel supply valve 47; this shifting can be effected manually, or, if desired, automatically. In the latter case, each regenerator outlet 44, 44' or 44'', as the case may be, is equipped with a 15 thermostat or thermocouple 27', adapted to secure periodically the actuation of a control switch 28', that is operatively connected, as shown in Fig. 4, to the linkage 46a that connects the associated damper 46 and valve 47. Assuming the burner 7 of regenerator 42 to have 20 been made operative for the combustion of fresh fuel in said regenerator, while the air supply is being forced through the other two regenerators 42' and 42'', it will be evident that at the start 25 of such combustion in the regenerator 42, the products of combustion leaving by way of branch 45 and outlet 44 will be relatively cool, having given up most of their heat to the checkerwork chambers 3 and 3a of said regenerator 42. Under 30 these conditions, said products of combustion will have no effect on the thermocouple 27'. However, after operation in this manner for some time, the combustion products will pass to the outlet 44 at a relatively high temperature, 35 sufficient to effect operatively the thermocouple 27', thereby to actuate the switch 28' for the shifting of the damper 46 and valve 47, whereby 40 said regenerator 42 is made effective as a heating agent for part or all of the air supplied under 45 pressure to the duct 43.

The system shown in Figs. 3 and 4 may, like the system shown in Figs. 1 and 2, divert a portion of the air from cold duct 43 to hot air duct 41, without passing it through any of the regenerators 42, 42' or 42''. In the case of Figs. 3 and 4 however, this air so diverted may receive heat from sources other than said regenerators, as, for instance, by connecting the duct 43 to a recuperator or other equivalent device 48, where- 50 in said cold air is circulated in countercurrent to waste hot gases coming, for example, from the furnaces or other fuel burning stations which are served by the system. Said air so heated in the device 48 then passes by way of pipe 49 to 55 the hot air duct 41, to augment the supply of hot air furnished by whichever of the regenerators 42, 42' and 42'' are then being used for air heating purposes. Thus, the amount of highly heated air from the regenerative preheaters will be 60 more sparingly required, and the rate of operation of these regenerators will be correspondingly reduced. The regulation of the amount of air by-passed through the pipe 49 to the hot air duct 41 may be secured automatically by a thermo- 65 stat or thermocouple 29' in said duct 41, said thermostat being suitably connected, as shown in Fig. 3, to an operating switch 30' for a damper 50 in the pipe 49. In the event of an overheated air supply in the duct 41, the thermocouple 29' 70 procures, through switch 30', the wider opening of damper 50, permitting the ingress in greater volume to duct 41 of air that is less highly heated than the air supplied by the regenerators; on the other hand, if the temperature in duct 41 75 falls too low, the thermocouple 29' will close,

or partly close, the damper 50, thereby causing a greater portion of the air supply from blower 11' to pass through one or more of the regenerators 42, 42' and 42''.

In both forms of the invention, as above de- 80 scribed, it should be noted that when a regenerator is being used for the burning of fuel, it is re- ceiving air from the same source as that which supplies the regenerator or regenerators used for the heating of said air,—notwithstanding the 85 fact that this fuel-burning regenerator is not directly connected with the pipe or duct (13 or 43) into which the entire air supply is blown. The fuel burning regenerator receives such air only after it has passed through the checkerwork 90 of one of the direct-connected regenerators. It should also be noted that the pressure maintained in such direct-connected regenerator or regenerators will be substantially that maintained in the hot air delivery duct (1 or 41), whereas the pres- 95 sure maintained in the fuel burning regenerator will be lower than the aforesaid pressure, by such an amount as is necessary to cause a flow from the hot air duct to said fuel burning regenerator of sufficient air to support the combustion of the 100 fuel being burned in said fuel burning regenerator. It will readily be seen that this flow will be materially checked by creation of pressure, due to expansion of the gases of combustion resulting from the chosen rate of fuel consumption in 105 this last-named regenerator, and that therefore adequate provision must be made to relieve this pressure through an outlet or stack (14 or 44) with a regulatable opening; by such regulation of the opening, the pressure in the fuel burning 110 regenerator can be made less than that in the air heating regenerator or regenerators, in order to cause flow of air from the latter to the former.

I claim:

1. In the regenerative preheating of air, the improvement which consists in burning fresh fuel to provide, in regenerators used alternately for the passage of a continuous air supply under pressure, the heat for such preheating, supporting 120 the combustion of said fuel by a portion of the air supply so heated, and maintaining by control of the combustion products leaving such fuel-burning regenerator a substantially constant pressure in such regenerator.

2. In the regenerative preheating of air, the improvement which consists in burning fresh fuel to provide, in regenerators used alternately for the passage of a continuous air supply under pressure, the heat for such preheating, support- 130 ing the combustion of said fuel by a portion of the air supply so heated, and maintaining, by control of the combustion products leaving such fuel-burning regenerator, a predetermined ratio between the volumes of fuel and air supplied 135 thereto.

3. In a regenerative air-preheating system, the combination with a plurality of regenerator chambers or passages used alternately for the passage of air and the burning of fuel, of means 140 for supplying air under pressure continuously to said system, means for diverting a portion of the pressure air supply, following its heating, to aid the combustion of the fuel so burned in the system, and pressure regulated means operative 145 on the outgoing combustion products for maintaining a predetermined ratio between the volume of air so diverted and the amount of fuel so burned.

4. In a regenerative air-preheating system, the 150

- combination with a plurality of regenerator chambers or passages used alternately for the passage of air and the burning of fuel, of means for supplying air under pressure continuously to said system, means for diverting a portion of the pressure air supply, following its heating, to aid the combustion of the fuel so burned in the system, and pressure-regulated means operative on the combustion products exhausted from said system for maintaining a predetermined ratio between the volume of air so diverted and the amount of fuel so burned. 5 80
5. In a system for the preheating of air, to produce high flame temperature from the combustion of fuel in the presence of said air, the combination with means for supplying air under pressure continuously to said system, of pressure-regulated means for automatically maintaining a predetermined ratio between the volume of such pressure air supply and the amount of fuel being burned with the aid of the heated air delivered by said system. 10 85
6. A system for the regenerative preheating of air, to produce high flame temperatures from the combustion of fuel in the presence of said air, comprising a plurality of regenerators, means for supplying air under pressure continuously to said system, means for directing a portion of said air supply through certain of said regenerators while burning fresh fuel in other of said regenerators, an offtake conduit common to all of said regenerators for delivering the preheated air emerging from the first-mentioned regenerators to the station or stations where fuel is to be burned, and to the fuel-burning regenerator or regenerators, and means for diverting directly to said offtake conduit, without passage through said regenerators, another portion of the air supplied under pressure to said system. 15 90
7. A system for the regenerative preheating of air, to produce high flame temperatures from the combustion of fuel in the presence of said air, comprising a plurality of regenerators, means for supplying air under pressure continuously to said system, means for directing a portion of said air supply through certain of said regenerators while burning fresh fuel in other of said regenerators, an offtake conduit common to all of said regenerators for delivering the preheated air emerging from the first-mentioned regenerators to the station or stations where fuel is to be burned, and to the fuel-burning regenerator or regenerators, and means for utilizing the combustion products from the fuel-burning station 20 95
- 55 or stations for heating another portion of the air supplied under pressure to said system, prior to the delivery of said last-mentioned portion to said offtake conduit. 100
8. A system for the regenerative preheating of air, to produce high flame temperatures from the combustion of fuel in the presence of said air, comprising a plurality of regenerators, means for directing a continuous supply of air under pressure to certain of said regenerators while burning fresh fuel in other of said regenerators in the presence of heated air delivered by said first-mentioned regenerators, and means for maintaining a lower pressure in said fuel-burning regenerator or regenerators than in said regenerator or regenerators used for the heating of said air. 105 110
9. A system for the regenerative preheating of air, to produce high flame temperatures from the combustion of fuel in the presence of said air, comprising a plurality of regenerators, means for directing a continuous supply of air under pressure to certain of said regenerators while burning fresh fuel in other of said regenerators in the presence of heated air delivered by said first-mentioned regenerators, and means for maintaining a lower pressure in said fuel-burning regenerator or regenerators than in said regenerator or regenerators used for the heating of said air. 115 120
10. A system for the regenerative preheating of air, to produce high flame temperatures from the combustion of fuel in the presence of said air, comprising a plurality of regenerators, means for blowing a continuous supply of air under pressure through certain of said regenerators while burning fresh fuel in other of said regenerators in the presence of heated air delivered by said first-mentioned regenerators, and means responsive to overheating of the air in said system for diverting to the air outlet thereof a portion of the pressure air supply, before the latter is heated. 125 130
11. A system for the regenerative preheating of air, to produce high flame temperatures from the combustion of fuel in the presence of said air, comprising a plurality of regenerators, means for blowing a continuous supply of air under pressure through certain of said regenerators while burning fresh fuel in other of said regenerators in the presence of heated air delivered by said first-mentioned regenerators, and means responsive to overheating of the air in said system for diverting to the air outlet thereof a portion of the pressure air supply, before the latter is heated, and means for maintaining a lower pressure in said fuel-burning regenerator or regenerators than in said regenerator or regenerators used for the heating of said air. 135 140
12. A system for the regenerative preheating of air, to produce high flame temperatures from the combustion of fuel in the presence of said air, comprising a pair of regenerators, means for blowing a continuous supply of air under pressure through one of said regenerators, while burning fresh fuel in the other of said regenerators in the presence of heated air delivered by said first-mentioned regenerator, means for interchanging the fuel-burning and air-heating functions of said regenerators, and means for maintaining a pressure differential between said regenerators, with the higher pressure always in the regenerator wherein the air supply is being heated. 145 150
13. A system for the regenerative preheating of air, to produce high flame temperatures from the combustion of fuel in the presence of said air, comprising a plurality of regenerators, means for blowing a continuous supply of air under pressure through certain of said regenerators while burning fresh fuel in the other of said regenerators in the presence of heated air delivered by the first-mentioned regenerator or regenerators, means for reversing said system to interchange the fuel-burning and air-heating functions of said regenerators, and means operative on the combustion products discharged by the fuel-burning regenerator or regenerators for maintaining a pressure differential between the fuel-burning regenerator or regenerators and the air-heating regenerator or regenerators. 155
14. A system for the regenerative preheating of air, to produce high flame temperatures from the combustion of fuel in the presence of said air, comprising a plurality of regenerators, means

for blowing a continuous supply of air under pressure through certain of said regenerators while burning fresh fuel in the other of said regenerators in the presence of heated air delivered by said first-mentioned regenerators, and means responsive to rise in temperature of the combustion products delivered by the fuel-burning regenerator or regenerators for reversing said system, to interchange the fuel-burning and air-heating functions of said regenerators.

15. A system for the regenerative preheating of air, to produce high flame temperatures from the combustion of fuel in the presence of said air, comprising a plurality of regenerators, means

15

for blowing a continuous supply of air under pressure through certain of said regenerators while burning fresh fuel in other of said regenerators in the presence of heated air delivered by said first-mentioned regenerators, 80 means for reversing said system, to interchange the air-heating and fuel-burning functions of said regenerators, and automatic means for regulating the amount of air supplied to said system in accordance with the amount of fuel that is being burned in the presence of the heated air supplied by said system. 85
